UNITED STATES PATENT OFFICE

119,120

DESIGN FOR A DRESS ENSEMBLE

Sydelle Rosen, New York, N. Y.

Application January 15, 1940, Serial No. 89,463

Term of patent 3½ years

To all whom it may concern:

Be it known that I, Sydelle Rosen, a citizen of the United States, residing in New York city, in the county of New York and State of New York, have invented a new, original, and ornamental Design for a Dress Ensemble, of which the following is a specification, reference being had to the accompanying drawing, forming part thereof.

Fig. 1 is a front view of a dress ensemble showing my design;

Fig. 2 is a rear view of Fig. 1;

Fig. 3 is a fragmentary side view of the coat portion of the ensemble illustrating the sleeve member thereof;

Fig. 4 is a front view of the dress member of the ensemble shown in Fig. 1, and
Fig. 5 is the rear view thereof.

The characteristic feature of my design resides in the combination on the ensemble disclosed of the specific coat member which is tucked and faced as shown.

I claim:

The ornamental design for a dress ensemble, substantially as shown and described.

SYDELLE ROSEN.
